US00D969762S

(12) **United States Design Patent** (10) Patent No.: **US D969,762 S**
(45) Date of Patent: **** Nov. 15, 2022**

(54) **POWER SEMICONDUCTOR PACKAGE**

- (71) Applicant: **Wolfspeed, Inc.**, Durham, NC (US)
(72) Inventor: **Kuldeep Saxena**, Sewickley, PA (US)
(73) Assignee: **Wolfspeed, Inc.**, Durham, NC (US)
(**) Term: **15 Years**
(21) Appl. No.: **29/811,014**
(22) Filed: **Oct. 11, 2021**

(57) **CLAIM**

The ornamental design for a power semiconductor package, as shown and described.

DESCRIPTION

FIG. 1 is a top perspective view of a power semiconductor package showing my new design;
FIG. 2 is a bottom perspective view thereof;
FIG. 3 is a top view thereof;
FIG. 4 is a bottom view thereof;
FIG. 5 is a front view thereof;
FIG. 6 is a rear view thereof;
FIG. 7 is a left side view thereof; and,
FIG. 8 is a right side view thereof.
